UNITED STATES PATENT OFFICE.

ULYSSES L. BERGER, OF WASHINGTON, DISTRICT OF COLUMBIA.

PICTURE-EXHIBITOR.

SPECIFICATION forming part of Letters Patent No. 733,802, dated July 14, 1903.

Application filed May 23, 1903. Serial No. 158,483. (No model.)

To all whom it may concern:

Be it known that I, ULYSSES L. BERGER, a citizen of the United States, residing at Washington, in the District of Columbia, have made 5 certain new and useful Improvements in Picture-Exhibitors, of which the following is a specification.

My invention is an improved apparatus for viewing pictures which are in the nature of 10 transparencies, the pictures proper being applied to glass plates or to translucent paper held duly stretched in a suitable frame.

The invention is embodied in certain features of construction, arrangement, and combination of parts, as hereinafter described, 15 and illustrated in the accompanying drawings, in which--

Figure 1 is a plan view of the apparatus, the cover of the box or body of the instrument being removed and the picture guide and support being shown extended laterally. Fig. 2 is a central vertical longitudinal section of the apparatus on line 2 2 of Fig. 1. Fig. 3 is a cross-section on the line 3 3 of Fig. 1.

The body of the instrument is an oblong rectangular box 1, which is constructed of some thin, light, and cheap material, preferably sheet metal. The box is provided near the end 2 with two transverse vertical partitions 3 and 4. The said partitions are separated by a narrow space and arranged parallel, so as to serve as guides for a picture support and guide 5. The latter is formed of thin sheet metal, its lower end being bent upward, as shown in Fig. 2, to form a guide for the picture x . The picture-support 5 is adapted to slide through a slot formed in the side of the box and between the partitions 3 and 4. It is prevented from being wholly drawn from the box by means of a tongue 6, which projects through a horizontal slot 7 in partition 3. A tube 8 extends from the partition 4 through the right-hand end 2^a of the box 1 and a slight distance beyond the same. This tube is supported by the said partition and the end of the box and is fixed in position. It is slotted longitudinally at 9. (See Fig. 1.) A shorter extension-tube 8^a is adapted to slide in the fixed tube 8. In Fig. 1 the extension 45 tube 8^a is shown drawn out by dotted lines and in Fig. 2 the same is closed or pushed in. A lens 10 is adapted to slide in the fixed tube

8, and for adjusting it it is provided with an arm 11, that extends laterally through a side slot 12, arranged longitudinally in the side 55 of the box. The outer end of said arm is provided with a thumb-piece 11^a for convenience of use in adjusting the lens toward or from the picture x . A curved lever 13 is pivoted upon a bracket or other suitable support 14 within the box and adapted to swing in a horizontal plane. Its longer arm projects through coincident slots in the partitions 3 and 4, and when a picture x is introduced it presses against or rests in contact 60 with the lever, as illustrated in Fig. 1. The arm 11, carrying the lens, as before described, is provided with a vertical pin or stud 15, (see Fig. 1,) which is adapted to work in contact with the lever, as will be presently described.

The manner of using the instrument is as follows: The picture guide and support 5 is first drawn out, as shown in Fig. 1. The picture is then laid therein in vertical position and slid horizontally into the space between the two partitions 3 and 4 until it reaches the position indicated in Fig. 1, the inner edge of the same being then in contact with the longer arm of the lever, as also indicated in Fig. 2. The slideable tube 8^a may then be adjusted as required. The end 2 of the box being then held to the light, the picture may be viewed through the coincident tubes 8 and 8^a, since the light necessary for 85 due illumination of the transparency will be admitted through the opening 1^a in the end of the box and through the coincident openings in the partitions 3 and 4. The lens 10 will be adjusted, by means of the attachment 11 90 11^a, toward or from the picture for the purpose of securing the desired optical effect, by which the picture is made to appear to the best advantage. By sliding the lens back and forth in the tube 8 the optical effect may 95 be changed at will, the figure or figures upon the transparency being thus enlarged or diminished in size correspondingly. It will be noted that the lens may be slid between the bracket 14, on which the lever 13 is pivoted, 100 and the nearest partition 4 without affecting the position of the lever or the picture x ; but when the lens is moved farther back its stud 15 will strike the shorter and more abruptly-

curved arm of the lever 13, so that the latter will be shifted on its pivot, with the result that the picture α will be pushed laterally outward in the guide-support 5, so that it will pass completely out of the range of vision of the person looking through the tube. It will be understood that this result is obtained when the lever and lens have reached the position indicated by dotted lines, Fig. 1. Thus the effect of a moving panorama or picture may be obtained by the simple manipulation of the lens—to wit, its adjustment in the tube 8—and the operation may be repeated as often as desired by pushing the picture α back to its original position (indicated by full lines, Fig. 1) and also adjusting the lens so that the stud or pin 15 is forward of the pivot of the lever. It will be seen that the apparatus is thus in the nature of a scientific toy, affording both instruction and amusement in an optical way.

Having thus described my invention, what I claim as new, and desire to secure by Letters Patent, is—

25 1. The improved picture-exhibitor comprising the box having longitudinal and vertical side slots, transverse partitions provided with openings, a fixed and longitudinally-slotted tube arranged at right angles to said partitions and extending through the box, a picture guide and support adapted to slide between the said partitions, a lens having a lateral arm and adapted to slide in the aforesaid tube, and a lever pivoted within the box and arranged as described for engagement with the picture and the arm of the lens, substantially as described.

2. The improved picture-exhibitor comprising a box having transverse partitions provided with central openings and a fixed tube arranged coincidently with said openings and provided with a lengthwise slot, a lens adapted to slide in the said tube and provided with a lateral arm for adjusting it as required, and a picture support and guide which is adapted to slide between said partitions and to be extended from the box laterally, substantially as shown and described.

3. The improved picture-exhibitor comprising the box, a tube arranged longitudinally therein and provided with a lengthwise slot, a lens adapted to slide in said tube, and a lateral arm connected therewith and adapted

to slide in a lengthwise slot provided in the side of the box, and a laterally-slidable picture guide and support arranged and adapted to work in a lateral, vertical slot of the box, substantially as described. 55

4. In a picture-exhibitor, the combination, with the box having a suitable picture guide 60 and support within the same, of a lever pivoted within the box and arranged for contact with the picture when introduced in the manner described, and means for adjusting said lever for the purpose of moving the picture 65 across the field of vision, substantially as shown and described.

5. The improved picture-exhibitor, comprising the box having suitable transverse guides for a picture, and a longitudinal tube 70 provided with a lengthwise slot, a lever pivoted within the tube and one of its arms projecting into the path of the picture, the lever being so curved that the other arm projects across the tube, and a device which is movable longitudinally of the box and provided with a projection adapted to work in contact with the lever, whereby the latter may be shifted in position for moving the picture in the manner described. 75

6. The improved picture-exhibitor comprising a suitable box having a lateral slot and interior guides for receiving and supporting a picture, a lengthwise tube which is slotted as described, a curved lever pivoted within 85 the box and projecting across the pathway of the picture and also across the tube, a lens which is slidable in the tube and provided with a lateral arm having a vertical projection adapted to work in contact with the lever, whereby, when the lens is adjusted away from the picture, the lever is shifted and the picture moved across the field of vision in the manner described. 90

7. In a picture-exhibitor, the combination, 95 with the box having a vertical side slot and a transverse partition arranged adjacently, of a picture guide and support adapted to slide in said slot and having a tongue projecting through a horizontal slot in the said 100 partition and serving as a stop and support for the picture-guide in the manner described.
